SANITARY FOOD CONTAINER

Harry T. Epstein, Roxbury, Mass.

Application February 13, 1935, Serial No. 6,381

3 Claims. (Cl. 206—44)

This invention relates to an improved sanitary food container, and the primary object of the invention is to provide a container for pies and other food-stuffs, by means of which such 5 pies or food-stuffs will be effectively protected from damage incident to their handling, as well as maintained in a cleaned and fresh condition.

A more specific object of the present invention is to provide a pie or like container which will 10 attractively display the contained pie or other food-stuffs while protecting the same against contamination or drying out, and whereby a plurality of the containers may be stacked one upon another without danger of crushing or otherwise 15 damaging the pies or other food-stuffs contained therein.

A still further object of the invention is to provide a container of the above character which is extremely simple and durable in construction, 20 efficient in use, and economical to manufacture.

Other objects and features of the present invention will become apparent from the following description when considered in connection with the accompanying drawing, in which:

25 Figure 1 is a top plan view of a sanitary food container constructed in accordance with the present invention.

Figure 2 is a central vertical section on line 2—2 of Figure 1; and

30 Figure 3 is a fragmentary vertical section illustrating a modification of the construction shown in Figures 1 and 2.

Referring in detail to the drawing, the present food container includes a plate 5 adapted to receive 35 the pie or other food-stuff to be packaged, which plate is illustrated by way of example as an ordinary pie plate pressed from a heavy grade of paper stock so as to be sufficiently rigid to properly support the pie or other food-stuff placed 40 thereon, and consisting of the usual flat bottom, flared side wall 6, and marginal flange 7.

The present container further includes an inner supporting band 8 provided at its upper edge with an inturned flange 9 upon which the marginal flange 7 of plate 5 rests, and the band 8 is of a width greater than the depth of plate 5 so that the latter is suspended at a slight elevation above the lower edge of said band 8. A "cellophane" or other transparent and hygroscopic sheet of a thin and flexible character is placed over the pie or other food-stuff in plate 5 as indicated at 10, thereby covering said pie or food-stuff so as to effectively exclude dust, dirt, moisture and the like therefrom. The margin of 55 this transparent and hygroscopic cover 10 is

turned downwardly around the marginal edge of the flange 7 of plate 5 and onto the outer surface of the inner supporting band 8, and an outer supporting band 11 is telescoped onto the inner supporting band 8 and the downturned margin of cover 10 so that said margin of cover 10 is tightly clamped between bands 8 and 11 to hold the cover 10 in place and maintain the portion thereof overlying the pie or food-stuff in plate 5 in a flat taut condition. The outer supporting band 11 10 is slightly wider than the inner band 8 and has an inturned flange 12 at its upper edge arranged to overlie the adjacent portion of cover 10 and to clamp the latter together with the flange 7 of plate 5 between the same and the opposed flange 15 9 of the inner supporting ring 8. The flange 12 of outer band 11 forms a rigid support upon which the bands 8 and 11 of another similar container may be seated, whereby a plurality of the containers may be arranged in stacked formation 20 without danger of damaging or crushing the pie or other food-stuff contained in the plates 5 of said containers. The supporting bands 8 and 11 are also preferably pressed from a heavy grade of paper stock so as to be sufficiently rigid 25 to support the plate 5 and the pie or other food-stuff placed in the latter. Obviously, the pie or other food-stuff in plate 5 will be clearly and attractively displayed through the cover 10.

In practice, the plate 5 with its contained food- 30 stuff is placed upon the flange 9 of band 8, whereupon the cover 10 is applied. The outer band 11 is then telescoped onto the inner band 8 and the marginal portion of cover 10. In this way the pie or food-stuff may be quickly and effectively 35 packaged in a manner to successfully carry out the stated objects of the invention. By removing the outer band 11 by upward displacement thereof, the cover 10 may be readily removed and access then had to the pie or other food-stuff placed in 40 plate 5.

If desired, the outer clamping and supporting band 11a, shown in Figure 3, may be provided with a rolled bead 13 or the like on the inner edge of its inturned flange 12a, said bead or the like 45 13 projecting in an upward direction so as to be received within the lower end of the similar clamping and supporting bands of a superimposed like form of container. In this way, stacking of a plurality of the containers may be 50 facilitated and relative lateral displacement of the stacked containers prevented to a material degree. In other words, the bead 13 is of an external diameter slightly less than the internal diameter of the associated inner supporting ring 55

8, and when a plurality of the containers are arranged in stacked formation, the bead 13 of one container will be snugly received within the clamping and supporting band 8 of the similar 5 container superposed thereon, thereby preventing ready relative lateral displacement of the superimposed containers. The invention is of course susceptible to further modification, and many changes are possible in the details of construction shown and described without departing from 10 the spirit and scope of the invention as claimed.

What I claim as new is:

1. A sanitary food container comprising an inner clamping and supporting band having an 15 inturned flange at its upper edge, a food-stuff receiving plate having a marginal flange resting on the inturned flange of said inner clamping and supporting band, a transparent cover overlying said plate and having its margin turned 20 downwardly around the marginal edge of the flange of said plate and onto the outer surface of said inner clamping and supporting band, and an outer clamping and supporting band telescoped onto said inner clamping and supporting band 25 and the downturned margin of said cover to maintain the latter and the plate in place.

2. A sanitary food container comprising an inner clamping and supporting band having an inturned flange at its upper edge, a food-stuff 30 receiving plate having a marginal flange resting on the inturned flange of said inner clamping and supporting band, a transparent cover overlying said plate and having its margin turned downwardly around the marginal edge of the flange 35 of said plate and onto the outer surface of said inner clamping and supporting band, and an

outer clamping and supporting band telescoped onto said inner clamping and supporting band and the downturned margin of said cover to maintain the latter and the plate in place, said outer clamping and supporting band having an in- 5 turned flange at its upper edge cooperating with the inturned flange of the inner clamping and supporting band to clamp the marginal flange of the plate and the adjacent portion of the cover therebetween. 10

3. A sanitary food container comprising an inner clamping and supporting band having an inturned flange at its upper edge, a food-stuff receiving plate having a marginal flange resting on the inturned flange of said inner clamping and supporting band, a transparent cover overlying said plate and having its margin turned downwardly around the marginal edge of the flange of said plate and onto the outer surface of said inner clamping and supporting band, and an outer clamping and supporting band telescoped onto said inner clamping and supporting band and the downturned margin of said cover to maintain the latter and the plate in place, said outer clamping and supporting band having an in- 15 turned flange at its upper edge cooperating with the inturned flange of the inner clamping and supporting band to clamp the marginal flange of the plate and the adjacent portion of the cover therebetween, said inturned flange of the outer 20 clamping and supporting band providing a rigid support to be engaged by the lower edges of the clamping and supporting bands of a superimposed similar container.
